United States Patent Office

Des. 181,500

Patented Nov. 19, 1957

181,500

LAUNDRY BASKET OR SIMILAR ARTICLE

Eugene H. Snyder, Columbus, Ohio, assignor to Columbus Plastic Products, Inc., Columbus, Ohio, a corporation of Ohio

Application March 15, 1956, Serial No. 40,617

Term of patent 14 years

(Cl. D58—4)

Fig. 1 is a perspective view of a laundry basket or similar article showing my new design;

Fig. 2 is a side elevational view;

Fig. 3 is an end elevational view; and

Fig. 4 is an enlarged fragmentary vertical sectional view taken along the line 4—4 of Fig. 2 and shown broken away for convenience of illustration.

I claim:

The ornamental design for a laundry basket or similar article, substantially as shown.
